UNITED STATES PATENT OFFICE

123,692

DESIGN FOR AN ELECTRIC REMOTE CON- TROLLER CASING

Leslie W. Gillette, Chicago, Ill.

Application September 9, 1940, Serial No. 94,911

Term of patent 7 years

To all whom it may concern:

Be it known that I, Leslie W. Gillette, a citizen of the United States and resident of Chicago, in the county of Cook and State of Illinois, have invented a new, original, and ornamental Design for Electric Remote Controller Casing, of which the following is a specification, reference being had to the accompanying drawing, forming part thereof.

Fig. 1 is a front elevational view of an electric remote controller casing showing my new design;

Fig. 2 is a top plan view;

Fig. 3 is a side elevational view. The side not shown is the same as Fig. 3.

The characteristic features of my design reside in the portions shown in solid black lines in the drawing.

The rear surface of the casing is plain.

I claim:

The ornamental design for an electric remote controller casing, as shown and described.

LESLIE W. GILLETTE.
